BAND-TYPE DISPLAY CARTON

Curtis M. Shanahan, Chagrin Falls, Ohio, assignor to Container Corporation of America, Chicago, Ill., a corporation of Delaware

Application July 9, 1952, Serial No. 297,910

6 Claims. (Cl. 206—47)

1

The invention herein disclosed in one of its presently preferred embodiments, is concerned with display cartons of that type which, as a band, tube or ring, may be wrapped or placed about a cylindrical or other shape of container, such as a can, to package the container by embracing, from top to bottom, opposite portions of the side wall or walls of the container and also to extend across the ends (top and bottom) of the container in relatively close embrace of such wall portions and ends, while exposing to view either the whole or a very substantial part of the container side wall or walls between the container ends.

Cartons of the type or character indicated above are usually constructed from strips or as strip-like blanks of material, such as paperboard, which for use in packaging ordinary flat-ended or substantially flat-ended containers such as cans with cylindrical or otherwise shaped side walls, are transversely scored to provide a pair of side wall panels and a pair of end wall panels, respectively designed to extend relatively parallel and closely adjacent to the opposite sides and the top and bottom walls of the container to be packaged. The band ends are commonly secured together by adhesive applied between a portion of one wall panel at one end of the strip blank and a glue flap connected to the other end of the blank thereby to effect the tube form.

While dependence might be placed upon a tight frictional embrace of the carton with and about the container to hold the container within the packaging carton and against accidental displacement from either of the open sides of the band, nevertheless it is usually desirable to provide a more positive means by which to insure against such accidental displacement. To that end various arrangements have been devised. Among those arrangements are those which employ some specially constructed and integral part of the carton to engage an end portion or some part of an end flange or seam of a can or like container, when the container is properly disposed within the band, to effect abutting and obstructing engagement with such portion or part of the container to prevent displacement from one or both open sides of the band. Such obstructing or "locking" devices are simple, economical and effective for their purpose.

It is sometimes desired not only to offer a principal commodity in a container packaged after the manner described above but also to offer with that principal commodity, some other or ancillary commodity such as an accessory item

2

or a premium item, the commodity and accessory or premium item together constituting a unit. Preferably the principal and ancillary items composing the unit are packaged together and, since the average consumer may wish to see both items before making the purchase, the ancillary item should be packaged with the principal or other item in some clearly visible or easily accessible manner.

10 The principal objects of this invention therefore, are to provide a simple and inexpensive band-type display carton of the character mentioned wherein a commodity in a container such as a can and some other commodity item may be packaged as a unit and in such manner that both packaged items may be clearly visible or accessible for inspection, wherein the packaged items are firmly secured in the carton, each against accidental displacement, wherein either of the 15 packaged items may serve to secure or aid in securing the other in the carton and against displacement therefrom, wherein one of the packaged items such as the ancillary item may be employed in cooperative relationship with the 20 wall panels of the carton to hold or aid in holding the carton in its open or expanded tube or ring form thereby to facilitate insertion of the 25 other or main item therein as well as for other purposes, and wherein the resultant carton with 30 its contents will be compact in arrangement and appearance and the package as a unit will be attractive as well as useful.

Many other objects as well as the advantages and uses of the invention both in the specific 35 form of this disclosure as well as in many modifications and variations constituting other embodiments, will be or should become apparent after reading the following description and claims and after viewing the drawings in which:

40 Fig. 1 is a perspective view, from a side and the rear, of a two item unit carton with a flat-ended cylindrical can or container disposed and secured therein partly by flaps or tongues which are attached to the top and bottom panels of 45 the carton and partly by a special construction and arrangement constituting part of the invention hereof, an ancillary item to be packaged in the carton and its position being indicated in dotted outline;

50 Fig. 2 is a top plan view of the carton and container shown in Fig. 1;

Fig. 3 is a sectional view of the carton alone taken along section line 3—3 of Fig. 2, the container being indicated in dotted outline; and

55 Fig. 4 is a top plan or developed view of a blank

as cut and scored for making the carton shown in the other figures.

Now, first referring to Fig. 4, the blank shown is cut from sheet material such as paperboard which may have been pre-cut into strips of a width at least equal to the maximum width of the blank or the blank may be cut directly from large sheets. Preferably the blanks are cut and scored simultaneously by the usual dies. As so cut and scored the body part of the band-type blank is an elongated strip consisting of a pair of side wall panels 5 and 7 each of generally rectangular shape, a top wall panel 6 and a bottom wall panel 8 also of generally rectangular shape, and a glue flap 9. In this form parallel score lines 10, 11, 12 and 13 extending transversely of the length of the strip or band and perpendicular to the side edges thereof, respectively, differentiate the side panel 5 from top panel 6, the top panel 6 from side panel 7, the side panel 7 from bottom panel 8 and bottom panel 8 from the glue flap 9. Folding of the carton into band, tube or ring form is effected along these several score lines.

Attached to and projecting laterally from what will be termed the front edge 14 and a score line 14' coextensive with the edge 14 of top panel 6, is a flap 15 the free edge 16 of which is a circular arc struck about a center which may lie medially on score line 14' on a radius equal to or slightly less than that of the inside edge surface of a can top end or lid flange F against which the edge 16 is to abut. The bottom panel 8 has a similar forwardly projecting flap 17 attached thereto along a score line 18, the free edge 19 of this flap also being arcuate about a center disposed medially on score line 18 and having a radius equal to or slightly less than the radius of the inside edge surface of a can bottom end flange F' against which the edge 19 is to abut. After the band blank has been folded into the tube or ring form and secured by adhesive between the glue flap 9 and the outer or bottom end of side panel 5, the two flaps 15 and 17 are swung downwardly and upwardly, respectively, and inwardly about score lines 14' and 18 to position them as indicated in Fig. 3, whereupon the can C to be packaged is pushed into the band to its diameter or slightly beyond at which time the natural resilience of the carton material will cause the flaps 15 and 17 to swing slightly in the reverse direction until their edges 16 and 19 abut against the respectively adjacent ends of the can and lie in abutting relation to adjacent can rim surfaces. The can and carton at this time are disposed in the relationship illustrated in Figs. 1 and 2 and, by reason of the abutting relationship between the arcuate edges of flaps 15 and 17 and the adjacent interior arcuate surfaces of the can end parts, the can is adequately locked and obstructed against accidental displacement from the front side of the band.

Projecting from the rear edge of side panel 7 and delineated therefrom by a score line 20, 20' coextensive with the rear edges 21 and 22, respectively, of the top and bottom panels 6 and 8, is what may be termed a combined item holder and blocking flap 23. Extending through the material across the score or hinge line 20-20' preferably at right angles thereto, and into both side panel 7 and flap 23 for suitable but equal distances are parallel slits 24, which, between them, define a strap-like member 26. The spacing between the slits 24 may be varied between wide limits depending upon the strength of the mate-

rial, the type of item to be carried and other factors, and, similarly, the end to end length of each slit and the distance between each slit and the adjacent marginal edge of flap 23 or end of panel 7 may be varied to accord with like factors. Extending between the adjacent ends of the slits are parallel score or hinge lines 25. If desired the slits may be widened into slots or even holes of substantial width, as may be preferred for the reception of special objects or for other reasons. Adjacent to the flap 23 the rear edge of top panel 6 may be notched as indicated at 27 for a purpose to be described.

The cartons as manufactured are completed in the tube or ring form by securing the glue flap 9 and the free end of panel 5 together. If they are not to be utilized immediately for packaging purposes and are to be stored or shipped it is convenient and space saving to fold them along score lines 10 and 12 or score lines 11 and 13 into a collapsed or flattened state from which it is a simple matter to expand or erect them into an open condition as shown in Figs. 1 to 3, inclusive. Where a carton is to be erected and commodity items such as the can C which, for instance, may be a can of paint, and a paint brush the handle of which is shown at B, are to be packaged therein it may be preferable first to insert the brush and thereafter to insert the can in its place. Assuming that this is the chosen procedure the first step will be to open or expand the band into tubular or ring form and the second step will be to displace the strap-like member 26 out of the plane of the panel 7 and flap 23 toward the adjacent open side of the band as shown in Figs. 1 and 2 in particular.

The strap-like member 26 being hinged respectively to the side panel 7 and flap 23 at its ends and, being scored along line 28' to hinge across its middle, will assume the angular shape shown in Figs. 1 to 3 inclusive and will cause the flap 23 to fold inwardly over the rear open side of the band to assume a position at or substantially at right angles to the side panel 7, the member 26 and the outer portion of flap 23 projecting over a part of the rear open side of the band and reducing the area of that opening. The article receiving pocket thus formed is aligned or in register with the notch 27 so that the brush handle B or the like may be slipped through the notch and into the pocket until its lower end encounters the upper surface of the bottom wall panel 8 upon which it may rest, the upper part of the brush or its handle projecting above the top of the carton. By weaving the brush handle or other object, as the case may be, into the pocket across the upper marginal portions of the panel 7 and flap 23, thence across (beneath) the strap-like member 26 and finally across the lower marginal portions of panel 7 and flap 23 into engagement with the bottom panel 8, these carton parts will be held firmly in the positions shown in Fig. 1.

The natural resilience of the material tending to cause the strap-like member 26 and the flap 23 to return to their original positions will provide a firm grip upon the brush or other item so that it will be held in its place. The flap 23, strap 26 and brush handle or other object in the pocket serve adequately to prevent egress of the can from the rear side of the band. Placement of the brush handle in position in the carton will hold the band in its open or expanded state while the can is being placed and secured within the band from the open front side as above

described. It will be observed that side panel 5 extends rearward beyond the edges 21 and 22 of the top and bottom panels of the carton. The purposes of this extension are to provide a degree of protection for the flap 23 and its associated parts, to increase the effective "footing" area of the package to prevent tipping and to give a substantial exposed area for printing and advertising material.

Since the specific embodiment pictured in the drawings and by the foregoing description is purely illustrative and since the invention is susceptible of wide application and incorporation into other forms of carton, it is desired that the invention be considered as limited only by its spirit and the scope of the appended claims.

I claim:

1. In combination, a band type carton including top and bottom wall panels, opposite side wall panels connecting the top and bottom wall panels, means carried by one of the first said wall panels for engagement with an adjacent end portion of a can-like container embraced by the several said panels of the carton for securing the container against accidental displacement from the band at one of its open sides, a flap member connected with one edge of one of said wall panels and extending into the path of displacement of the container from the carton at the opposite side of the band, a strap-like member connected at one end with and formed partly from within the bounds of said flap member and connected at its other end with and formed partly from within the bounds of the wall panel to which said flap member is connected, and a relatively rigid commodity item having a length greater than the width of said strap-like member disposed between said strap and the adjacent parts of the flap to retain said flap in the path of displacement of said container at the said opposite side of the band.

2. In combination, a band-type carton including top and bottom wall panels, opposite side wall panels connecting the top and bottom wall panels, means carried by said top wall panel for engagement with an adjacent end portion of a can-like container embraced by the several said panels of the carton for securing the container against accidental displacement from the band at one of its open sides, a flap member connected with one edge of one of said side wall panels and extending into the path of displacement of the container from the carton at the opposite side of the band, a strap-like member connected at one end with and formed partly from within the bounds of said flap member and connected at its other end with and formed partly from within the bounds of the side wall panel to which said flap member is connected, and a relatively rigid commodity item having a length greater than the width of said strap-like member disposed between said strap and the adjacent parts of the flap to retain said flap in the path of displacement of said container at the said opposite side of the band.

3. In combination, a band-type carton including top and bottom wall panels, opposite side wall panels connecting the top and bottom wall panels, means carried by said bottom wall panel for en-

gagement with an adjacent end portion of a can-like container embraced by the several said panels of the carton for securing the container against accidental displacement from the band at one of its open sides, a flap member connected with one edge of one of said side wall panels and extending into the path of displacement of the container from the carton at the opposite side of the band, a strap-like member connected at one end with and formed partly from within the bounds of said flap member and connected at its other end with and formed partly from within the bounds of the side wall panel to which said flap member is connected, and a relatively rigid commodity item having a length greater than the width of said strap-like member disposed between said strap and the adjacent parts of the flap to retain said flap in the path of displacement of said container at the said opposite side of the band.

4. A blank for the formation of a band-type carton of the character described comprising, a strip of material cut and scored to provide a pair of side panels and a pair of end panels alternating with one another, one of said panels having a flap extending from one edge thereof and connected thereto along a coextensive score line, said flap and an adjacent part of the panel to which it is connected being slit transversely of and across said score line along substantially parallel and substantially coextensive spaced paths, the material between said slits being scored transversely of the slits adjacent to the ends thereof.

5. A blank for the formation of a band-type carton of the character described comprising, a strip of material cut and scored to provide a pair of side panels and a pair of end panels alternating with one another, one of said side panels having a flap extending from one edge thereof and connected thereto along a coextensive score line, said flap and an adjacent part of the side panel to which it is connected being slit transversely of and across said score line along substantially parallel and substantially coextensive spaced paths, the material between said slits being scored transversely of the slits adjacent to the ends thereof.

6. A blank for the formation of a band-type carton of the character described comprising, a strip of material cut and scored to provide a pair of side panels and a pair of end panels alternating with one another, one of said side panels having a flap extending from one edge thereof and connected thereto along a coextensive score line, said flap and an adjacent part of the side panel to which it is connected being slit transversely of and across said score line along substantially parallel and substantially coextensive spaced paths, the material between said slits being scored transversely of the slits adjacent to the ends thereof, the free edge of one of said end panels adjacent to said flap being notched.
